(57) **CLAIM**

The ornamental design for a seat for stool, as shown and described.

DESCRIPTION

FIG. 1 is a perspective view of the top, front and right side of a seat for stool according my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a view similar to FIG. 2 with the seat in position on a stool.

The elements shown in broken lines are for illustrative purposes only and form no part of the claimed design.

1 Claim, 4 Drawing Sheets

FIG. 1

FIG. 2
